UNITED STATES PATENT OFFICE.

DAVID BEAUREGARD FALK, OF SAVANNAH, GEORGIA.

GARMENT-BAG

1,070,790.

Specification of Letters Patent.

Patented Aug. 19, 1913.

Application filed December 12, 1912. Serial No. 736,314.

To all whom it may concern:

Be it known that I, DAVID B. FALK, a citizen of the United States, and a resident of Savannah, in the county of Chatham and State of Georgia, have invented certain new and useful Improvements in Garment-Bags, of which the following is a specification.

This invention is an improvement in garment bags or bags for holding garments and will be found useful in the delivery of garments as well as in protecting garments temporarily or from season to season as may be desired; and the invention consists in certain novel constructions and combinations of parts as will be hereinafter described and claimed.

In the drawings Figure 1 is a perspective view of the improved bag open ready to receive a garment. Fig. 2 is a perspective 20 view of the bag shown in Fig. 1 as in use with the garment inclosed and with the garment hanger in position. Fig. 3 is a detail perspective view showing a somewhat different construction from that presented in Figs. 1 and 2 in that the bottom flap is extended up sufficiently to overlap the top flap and permit securing both flaps together or by one set of fastenings. Fig. 4 is a detail perspective view of a somewhat different 25 construction of bag ready to receive the garment. Fig. 5 is a perspective view of the bag shown in Fig. 4 as in use. Fig. 6 is a cross section on about line 6—6 of Fig. 4. Fig. 7 is a cross section on about line 7—7 30 of Fig. 5. Fig. 8 is a detail section on about line 8—8 of Fig. 5. Fig. 9 shows a different form of fastening means from that shown in Figs. 1 and 4. Fig. 10 shows a bag made without the bellows at the sides.

The bag may be made of any suitable material preferably of stout paper and comprises, in the construction shown in Figs. 1 and 2, a body portion A which may be regarded as in tubular form, open at the bottom A' and at the top A², having at its sides the bellows folds A³ and provided with a bottom flap B for closing the lower end of the body A and with a top flap C for closing the upper end of the body A. The bellows 40 folds at A³ may be preferred because they permit the swelling out of the bag as shown in Figs. 2, 5 and 7 to accommodate a number of garments but manifestly these bellows folds may be omitted as shown for instance 45 in Fig. 10 of the drawings, without departing from some of the principles of my in-

vention. The bottom flap B may be of the length shown in Figs. 1 and 2 so that it will terminate alongside the tubular body portion below its middle but in some instances it may be preferred to reinforce the bag by 50 extending the bottom flap B as shown at B¹⁰ in Fig. 3 so that the upper end of the bottom flap may overlap the top flap C as will be understood from Fig. 3 and thus not only reinforce the body of the bag but also reinforce the top flap and aid in securing a practically dust tight closure at the upper end of the bag as will be understood from said Fig. 3 of the drawings. This also permits 55 the use of one set of fasteners to secure both flaps, see Fig. 3.

In the use of the construction shown in Figs. 1 and 2, the garment is suitably supported on a hanger D and may be drawn up 60 through the lower open end of the body A to the position shown in Fig. 2 and the bottom flap B and the top flap C be closed as shown in Fig. 2 and sealed either by a suitable adhesive mucilage or paste, an adhesive being shown at B' and C' in Fig. 1, or if desired, other forms of fastenings such, for instance, as the popular button and cord fastening such as shown in Fig. 9, may be utilized in securing the top and bottom flaps 65 when the latter are closed as will be understood from the drawings, see Fig. 3 showing one fastening for both flaps.

To permit the passage of the shank of the garment supporter D with respect to the top 70 flap C, it is preferred to make the said top flap in two side sections or tongues arranged side by side and separated at their meeting edges on about the median line of the bag as shown in Figs. 1 and 2 in such manner as to 75 permit the passage of the garment supporter shank. Manifestly the tongues or sections may be formed as shown at E in Figs. 4 and 5 with their meeting edges separated simply by a cut or slit formed parallel 80 to the direction of length of the body portion of the bag, but it is preferred to make the tongues C¹⁰ and C¹¹ of the top flap C as shown in Fig. 1 to overlap at their meeting edges so they will thus close the gap between 85 the separated adjacent edges of the tongues and so render the bag more nearly dust proof as well as forming a reinforce for each other at the meeting edges of the tongues as will be understood from Figs. 1 and 2 of the 90 drawings. In thus forming the tongues to overlap, their inner edges are preferably 95

diagonal to the direction of length of the bag and flaring outwardly from the central or median line of the bag at C¹² as will be understood from Fig. 1 of the drawings, so that I thus secure a considerable lap or extension of both of the tongues beyond the median line of the bag to increase the reinforcing effect as well as to prevent as far as possible the ingress of dust when the bag is in use.

I claim:

1. A garment bag comprising a body portion open at both ends and having bellows folds at its sides and provided with a bottom flap for closing its lower end and with a top flap for closing its upper end, said top flap being composed of two tongues separated at their adjacent edges midway between the sides of the flap and having their said edges formed on diagonal lines flaring in opposite directions away from the median line of the bag whereby there are provided overlapping portions at the inner meeting edges of the tongues, the separated inner edges of the tongues forming a passage for the shank of a garment hanger, which passage extends to the folding line between the body of the bag and the top flap, substantially as and for the purposes set forth.
2. A garment bag comprising a body portion open at both ends and having a bottom flap for closing its lower end and a top flap for closing its upper end, the top flap being composed of two tongues separated at their adjacent edges midway between the

sides of the flap for the passage of a garment hanger shank with said tongues overlapping at their meeting edges to form a closure for the joint at such point, the passage for the garment hanger shank extending to the folding line between the body of the bag and the top flap, substantially as set forth. 40

3. A garment bag having a top flap for closing its upper end composed of two 45 tongues or sections separated at their adjacent edges forming a passage between them for the shank of a garment hanger, such passage extending to the folding line between the body of the bag and the top flap, 50 one of said tongues overlapping the other laterally at said adjacent edges, substantially as set forth.

4. A garment bag comprising a body portion open at its upper and lower ends, a top 55 flap for closing the upper end of said body portion, said top flap being composed of two tongues or sections separated at their adjacent edges to form a passage between them for the shank of a garment hanger, and a 60 bottom flap for closing the lower end of the body, said bottom flap being of sufficient length to extend up over and overlap the top flap when the latter is adjusted to position for use, substantially as set forth.

DAVID BEAUREGARD FALK.
